UNITED STATES PATENT OFFICE.

JOHN J. N. VAN HAMERSVELD, OF CLEVELAND HEIGHTS, OHIO, ASSIGNOR, BY MESNE ASSIGNMENTS, TO THE ROTOR AIR TOOL COMPANY, OF CLEVELAND, OHIO, A CORPORATION OF OHIO.

ROTARY MOTOR TOOL.

Application filed September 30, 1926. Serial No. 138,724.

This invention relates to a rotary motor tool and has for one of its objects to provide an improved reversible tool with a gear reduction particularly adapted for drilling, 5 reaming, tapping, and the like.

A further object is to provide a tool of this character which embodies to a high degree the features of compactness, accessibility, simplicity of construction and ease of assembly. 10 It is a further object to provide means whereby the speed ratio of the gearing between the motor spindle and the tool spindle may be readily changed.

Still further, the invention aims to arrange 15 in an efficient manner the reduction gearing, valve, handle and inlet and exhaust passageways so as to avoid manufacturing complications, minimum length of passageways from the point of entrance to the point of exhaust 20 of the air, as well as ease of operation of the valve and at the same time admit of the use of reduction gearing and a housing enclosing the same which adds little to the size of the structure as a whole. It is a further object 25 also to arrange the parts just enumerated so as to admit of the use of a standardized motor adaptable for other types of tools not requiring the reversible and geared reduction features, the added features of reversibility and 30 gear reduction being accomplished with very few changes in the standardized motor, and mainly by the introduction or application of certain parts in the nature of an attachment to the standardized motor.

The above and other objects are attained 35 by my invention which may be here briefly summarized as consisting in certain novel details of construction and combinations and arrangements of parts which will be described 40 in the specification and set forth in the appended claims.

In the accompanying sheets of drawings illustrating an embodiment which operates effectively, Fig. 1 is a top plan view of the 45 rotary motor tool.

Fig. 2 is an end view looking toward the left of Fig. 1;

Fig. 3 is a side elevation;

Fig. 4 is a longitudinal sectional view on 50 an enlarged scale substantially along the line 4-4 of Fig. 1;

Fig. 5 is a transverse sectional view substantially along the line 5-5 of Fig. 4;

Fig. 6 is a fragmentary sectional view sub-

stantially along the line 6-6 of Fig. 5 omitting the cover plate for the valve operating mechanism;

Fig. 7 is an elevation of the cover plate omitted from Fig. 6;

Fig. 8 is a plan view showing a portion of Fig. 1 with the top plate of the motor removed and with a portion of the gear housing and the valve in section;

Fig. 9 is a sectional view substantially along the line 9-9 of Fig. 8;

Fig. 10 is a fragmentary sectional view substantially along the line 10-10 of Fig. 8;

Fig. 11 is a perspective view of the valve;

Fig. 12 is a transverse sectional view of the valve and its associated sleeve substantially along the line 12-12 of Fig. 8 showing the valve in one of its working positions for rotation of the tool spindle in one direction;

Fig. 13 is a similar view with the valve in another of its working positions corresponding to the rotation of the tool spindle in the opposite direction;

Fig. 14 is a similar sectional view substantially along the line 14-14 of Fig. 8; and

Fig. 15 is a similar sectional view substantially along the line 15-15 of Fig. 8.

Referring now to the drawings, and first to the main or general construction, it will be seen that the rotary motor tool herein illustrated includes a motor proper 20, at the front of which is a gear housing 21 with laterally projecting cross bar handles 22 and 23 and with a forward extension 24 for supporting a tool holding member here illustrated as a taper shank socket 25. At the rear end of the motor is a carrying handle 26.

The motor itself is substantially the same as the motor illustrated in and constituting the subject matter of the prior application filed in the names of Van Hamersveld and Cook, Serial No. 70,642, (Patent No. 1,653,748, granted December 27, 1927), the motor therein illustrated being designed particularly for use with tools not requiring reversibility, as for example, when used for grinding and buffing purposes; or the like. As the motor is quite similar to that referred to in the prior application, a brief description of the same will here suffice. It includes a one-piece body 27 with a straight cylinder bore extending from end to end therethrough, which bore receives two pistons 28 eccentrically mounted on a motor spindle 29 which, in

this instance, is supported by a ball bearing 30 arranged between the pistons and by an outer ball bearing 31 supported by a front bracket 32.

5 The inner bearing 30 is mounted in a bearing housing 33 fixed in position by a screw 34 extending through the central wall 35 of the motor body midway of the ends thereof or centrally with respect to the pistons which 10 are arranged on opposite sides of the inner bearing 30 and its housing 33.

The cylinder body has an extension on one side and through this extension are drilled from end to end pasageways 36 and 37 for the 15 motive fluid, which is generally compressed air, see Fig. 9. Between the passageways 36 and 37 two radially disposed guideways are formed between the outer face of the extension and the cylinder bore, and in these passageways are arranged two radially movable 20 blades 38. The passageway 36 is intersected by a series of passageways 39 drilled from the outer face of the extension to the cylinder bore and the passageway 37 is intersected by 25 a series of passageways 40 drilled from the outer face of the extension to the cylinder bore. The outer face of the extension is covered by a cover plate 41 forming a closure for the outer ends of the slots receiving the blades 38 and covering also the outer ends of the 30 passageways 39 and 40 as well as the screw 34 which positions the bearing housing 33. The ends of the motor body are engaged by cylinder plates 42 which are arranged between the 35 motor body and the front bracket 32 and rear handle 26 respectively, these cylinder plates closing the ends of the radial slots receiving the radially movable blades 38.

Coming now to the structure more directly 40 involving the present improvements, it will be seen that the gear housing 21 already referred to is composed of two portions, including a main front portion and a rear portion formed by the bracket 32. These two parts 45 of the housing, the motor body 27, the cylinder plates 42 and the carrying handle 26 are secured together by axially disposed bolts 43, 44 and 45. The bolts 43, of which there are two, arranged near the top of the motor, extend 50 entirely through the device, including the carrying handle at the rear and the two parts of the housing 21 at the front. The bolts 44, of which there are two, located below the bolts 43, extend from the rear through 55 the bracket 32 only, for a purpose which will appear presently, and the bolts 45 extend through the lower portion of the two parts forming the housing, as illustrated most clearly in Fig. 3.

60 The reduction gearing consists of two pairs of meshing gears arranged in two planes, one forwardly of the other, the rear pair including a pinion 46 which is preferably formed direct on the motor spindle 29, and a relatively large gear 47 meshing therewith and

arranged on a countershaft 48 supported in ball bearings 49 and 50 mounted respectively in the front and rear portions of the housing 21. The other pair of gears includes a pinion 51, also on the countershaft 48, meshing with 70 a gear 52 which in this instance is larger than the gear 51, and is secured to the rear end of the tool spindle 53 to which the taper shank socket 25 is attached. The spindle 53 extends through a forward sleeve-like extension 54 of 75 the front or main member of the housing 21, and it is supported by two ball bearings 55 and 56 mounted in this extension, the bearing 55 being adjacent the gear 52 and the bearing 56 being adjacent the forward end of the extension 54, which is closed by a suitable packing ring and nut 57.

Referring particularly to Fig. 5, it will be seen that the main portion of the gear housing 21 has integral lateral extensions forming the 80 cross bar handles 22 and 23 and that it has also at the top an integral extension 58 which forms a housing for a valve 59 which is a small cylinder valve axially rotatable and disposed transversely of the tool above the reduction gearing. The valve 59 is adapted to rotate in a sleeve 60 fixed in a cylindrical opening bored into the extension 58, one end of this opening being closed by a plug 61. The valve at the opposite end is provided with 85 an extension 62 carrying at its outer end a gear segment 63 normally closed by a cover plate 64 and engaging teeth formed on a valve controlling sleeve 65 rotatably supported on the cross bar handle 22. This sleeve is held 90 from endwise movement on the cross bar handle 22 by a nut 66 which is screwed onto the end thereof.

By reference to Figs. 5 and 6, it will be observed that the inner end of the valve controlling sleeve 65 is provided opposite the toothed portion engaging the gear segment 63 with notches 67 which are adapted to be engaged by a spring-pressed detent 67, the notches corresponding to the two working 105 and neutral positions of the valve so that the detent will hold the valve in these main positions without liability of being moved by vibration.

The air or other motive fluid is supplied 110 through the cross bar handle 23, the latter being provided with a passageway 68 which extends from the outer end longitudinally of this cross bar handle into the body portion of the gear housing, and then curving upwardly, the inner end registering with a port 69 in the fixed sleeve 60 which receives the valve 59. The cross bar handle 23 is preferably provided also with a longitudinally extending lubricating chamber 70, the lubricant 115 from which is adapted to pass into the stream of air flowing through the passageway 68 at a rate which can be controlled by a needle valve 71.

The air, after passing from the valve 120

through the motor and back to the valve in a manner to be explained, leaves the tool through a fairly large passageway 72 which extends through the cross bar handle 22 after 5 passing through a screen 73 (provided to keep out dirt) which is held in position against the end of the cross bar handle by the nut 66, as illustrated in Fig. 5. It will be observed that the passageway 72 is provided with a series of ribs 74 which are spaced apart axially of the passageway and project in opposite directions in overlapping relation so as to provide a baffling effect to reduce the noise of the exhaust.

15 The inner end of the exhaust passageway 72 extends into the main portion of the gear housing 21 where it curves upwardly and is in registration with a port 75 in the sleeve 60 receiving the valve 59. The inner ends of 20 the inlet passageway 68 through cross bar handle 23 and of the exhaust passageway 72 extending through the cross bar handle 22 are close to each other, being separated, however, by a web 76 seen in Fig. 5.

25 A point to be noted is that the inner portions of the inlet and exhaust passageways 68 and 72 are in the space between the two pairs of reduction gears immediately beneath the valve whose axis also lies between these 30 two pairs of gears.

In the end of the valve 59 adjacent the nut 61 is a chamber 77, and in the wall of this chamber is a port 78 which at all times registers with the port 69 in sleeve 60. Extending from the end of chamber 77 and communicating therewith there is a narrow, elongated chamber extension 79 which extends to the periphery of the valve, as best shown in Figs. 8, 12 and 13, and partially surrounding this extension 79 of the chamber is an arc-shaped passageway 80. Opposite the slot or extension 79, the sleeve 60 is provided with two ports 81 and 82, either of which is adapted to function as an inlet port, in addition to the port 75 already referred to, this last mentioned port being at all times in communication with the passageway 80 of the valve.

By reference to Fig. 4, it will be observed 50 that the ports 81 and 82 in the sleeve 60 register with two passageways 84 and 85 in the adjacent portion of the wall of the housing 21 and that these passageways are in alignment with passageways 86 and 87 55 formed in the bracket portion 32 of the housing 21. These two passageways 86 and 87 are extended laterally, as shown in Fig. 10, and extend to openings 88 and 89 which register with the passageways 36 and 37 extending through the cylinder body, registering openings being formed also, of course, through the intermediate cylinder plate 42. There will be presently explained the course 60 of the motive fluid through the valve and motor for each direction of operation.

The chamber 77 of the valve is additionally provided with two ports 90, one of which is adapted to register with a port 91 in the valve sleeve 60 when the valve is in either of its two working positions. This port 91 70 is connected by a passageway 92 through the bracket portion 32 of the gear housing to a passageway 93 which extends part way through the cylinder body and is connected by two ports 94 to the upper portions of the 75 slots receiving the reciprocating blades 38 so that whenever the motor is in operation the pressure of the motive fluid will be behind these blades so as to cushion the outward strokes of the blades and to hold them 80 down into engagement with the rotors, this occurring, of course, with either direction of rotation of the rotors, (see Figs. 8, 9 and 10).

When the valve is in the position indicated in Figs. 4 and 8, it is in neutral position in 85 which event no air is supplied to the motor, but when it is turned to the position shown in Fig. 13, air passes from the chamber 80 and the slot 79 of the valve, through the port 82, and by way of the passageways 85, 90 87, 89, 37 and 40 to the cylinders, thus rotating the cylinders in one direction. At the same time exhaust occurs from the cylinders by way of the passageways 39, 36, 88 and 84 to the port 81 of sleeve 60, and by passageway 80 of the valve to the exhaust port 75 of the valve sleeve 60, and into the exhaust passageway 72 in cross bar handle 22, from which the air quietly escapes.

When the valve is turned to the position 100 shown in Fig. 12, the air passes through the motor in the reverse direction, being supplied to the passageway 81 extending through the cylinder body and exhausted from the passageway 89 and being conducted through the 105 valve to the outlet passageway 72, as before.

By turning the sleeve 65 slightly, motion is transmitted to the valve by reason of the geared connection of these parts so that it is convenient for the operator to position the 110 valve either in neutral position or in either of its running positions. As previously stated, regardless of the direction in which the motor is run, air pressure is exerted down on the reciprocating blades 38, the air supply 115 to the outer ends of the slots containing the blades being shut off when the valve is in neutral position, as will be seen by reference to Fig. 15, so as to prevent leakage of air when the motor is not in use.

With the construction which I have provided, it is only necessary to remove the nuts from the ends of the bolts 43 and 45 to permit removal of the body portion of the gear housing from that portion thereof formed by the 125 bracket 32, and inasmuch as there is ample space between the pinion or gear 51 and the lower part of the gear housing, as shown in Fig. 4, it will be obvious that the ratios of gears 51 and 52 can be changed to vary the 130

speed ratios between the motor spindle and the tool spindle.

By reference particularly to Figs. 1, 2 and 3, it will be noted that the reduction gearing and gear housing, even though the valve is incorporated in it, add very little to the size of the tool, rendering it very compact. This high degree of compactness is due in large measure to the advantageous arrangement of 10 the valve and the various air passages extending to and from the valve through the cross bar handles and especially as the otherwise unoccupied space between the two pairs of gears is made use of by extending portions 15 of the passageways into this space to an extent well illustrated in Fig. 5, thus making it possible to lower the valve considerably and to condense the structure generally as regards a construction wherein these passageways are 20 outside of the space occupied by the gearing. Not only does this arrangement, i. e., the arrangement wherein these air passageways are extended for a distance between the two pairs of gears, add materially to the feature of compactness, but the lowering of the valve permitted by this arrangement brings the passageways to the gear housing, including the bracket 25 32, substantially in line with the main passageways extending longitudinally through the 30 cylinder body, thereby permitting the air to pass to and from the cylinders in the most direct fashion. This, of course, adds to the efficiency of the motor by reducing loss in power by the friction of the air in passing 35 through the motor.

It might be noted in conclusion that by dividing the gear housing as shown in the drawings and described above, and with the manner of securing the parts through the medium 40 of the bolts 43, 44 and 45, it is possible not only to separate the parts of the housing and expose the gearing for the purpose of changing the speed ratios or for repair purposes, but this construction allows the tool to be first 45 assembled into two unit assemblies consisting in effect of the parts on opposite sides of the parting line shown in Fig. 4 where the two parts of the gear housing are united. The 50 countershaft with the gears 47 and 51 may be made a part of either of these unit assemblies.

While I have shown the preferred construction and one which operates at high efficiency, I do not desire to be confined to the precise 55 details shown but aim in my claims to cover all modifications which do not involve a departure from the spirit and scope of the invention.

Having thus described my invention, I 60 claim:

1. In a rotary motor tool, a fluid pressure motor comprising a housing and a rotor including a motor spindle, a tool spindle, reduction gearing between said spindles, a housing 65 for said gearing secured to the end of the

motor housing, and cross bar handles extending from opposite sides of the gear housing.

2. In a rotary motor tool, a fluid pressure motor comprising a housing and a rotor including a motor spindle, a tool spindle, reduction gearing between said spindles, a housing enclosing said gearing and attached to the end of the motor housing, the gear housing and motor housing having connecting passageways for the motive fluid. 70 75

3. In a rotary motor tool, a fluid pressure motor comprising a housing and a rotor including a motor spindle, a tool spindle, reduction gearing connecting them, a housing enclosing said gearing and attached to the end of the motor housing, the gear housing and motor housing having communicating passageways for the motive fluid, and a valve carried by the gear housing and controlling the flow of motive fluid through said passage- 80 85 way.

4. In a rotary motor tool, a fluid pressure motor comprising a housing and a rotor including a motor spindle, a tool spindle, gearing connecting the spindles, a housing enclosing the gearing and attached to the end of the motor housing, passageways for both the supply and exhaust of motive fluid in the motor housing, similar passageways in the gear housing and communicating with the first 90 95 named passageways, and a reversing valve carried by the gear housing and controlling the supply and exhaust of motive fluid and the direction of rotation.

5. In a rotary motor tool, a fluid pressure motor comprising a housing and a rotor including a motor spindle, a tool spindle, gearing connecting them, a gear housing secured to the end of the motor housing, cross bar handles secured to the gear housing, passageways for the motive fluid formed in the motor housing and gear housing in communicative relation, and a valve carried by the gear housing and controlling the passage of fluid through the passageways. 100 105 110

6. In a rotary motor tool, a fluid pressure motor comprising a housing and a rotor including a motor spindle, a tool spindle, gearing connecting the spindles, a housing enclosing the gearing and attached to the end of the motor housing, a cross bar handle secured to the gearing housing and having a fluid passageway extending therethrough, a valve carried by the gear housing and communicating with the passageway of said handle and, communicating passageways formed in the gear housing and in the motor housing, the flow of motive fluid through said passageway being controlled by the valve. 115 120

7. In a rotary motor tool, a fluid pressure 125 motor comprising a housing and a rotor including a spindle, a tool spindle, gearing connecting them, a housing enclosing the gear- ing and attached to the end of the motor housing, a pair of cross bar handles secured

to the gear housing and one provided with a fluid supply passageway and the other with an exhaust passageway, a reversing valve carried by the gear housing, supply and exhaust passageways formed in the gear housing and motor housing, those in one housing being in communicating relation with those

in the other housing, one of the handles carrying a valve actuating member which is connected with the valve.

10

In testimony whereof, I hereunto affix my signature.

JOHN J. N. VAN HAMERSVELD.
